APPLIQUE OR SIMILAR ARTICLE

Salvador J. Reynoso, Chicago, Ill.

Application April 15, 1955, Serial No. 35,539

Term of patent 7 years

(Cl. D3—9)

The figure is a plan view of the applique or similar article, showing my new design, the dotted lines showing the application of a name to the floral design.

The article itself has no substantial thickness.

The dominant features of this design reside in the portions shown in full lines.

I claim:

The ornamental design for an applique or similar article, as shown and described.
